UNITED STATES PATENT OFFICE.

GEORGE J. GRIFFITHS AND CHARLES H. RODERICK, OF WOODSTOCK, ILLINOIS, ASSIGNEES TO THE OLIVER TYPEWRITER COMPANY, OF CHICAGO, ILLINOIS, A CORPORATION OF ILLINOIS.

RIBBON-ACTUATING MECHANISM FOR TYPE-WRITERS.

1,110,132.

Specification of Letters Patent.

Patented Sept. 8, 1914.

Application filed January 19, 1914. Serial No. 813,065.

To all whom it may concern:

Be it known that we, GEORGE J. GRIFFITHS and CHARLES H. RODERICK, citizens of the United States, and residents of Woodstock, in the county of McHenry and State of Illinois, have jointly invented certain new and useful Improvements in Ribbon-Actuating Mechanism for Type-Writers; and we do hereby declare that the following is a full, clear, and exact description thereof, reference being had to the accompanying drawings, and to the letters of reference marked thereon, which form a part of this specification.

15 This invention relates to ribbon actuating mechanism for typewriting machines intended more particularly for application to machines of the kind known as the "Oliver" typewriter, such as is shown and described 20 in the patent granted to Thomas Oliver, No. 599,863, dated March 1st, 1898, and of that class in which the direction of movement of the ribbon may be reversed by winding the ribbon first upon one and then upon the 25 other of the ribbon spools arranged at opposite sides of the machine.

The object of the invention is to improve and simplify the construction of the type of ribbon actuating mechanism, above referred to, in several particulars as will hereinafter appear.

Although the ribbon actuating mechanism herein referred to is particularly applicable to "Oliver" typewriting machines, it is to 35 be understood that said mechanism is applicable to machines differing in construction from such "Oliver" machines.

The invention consists in the matters hereinafter described and more particularly 40 pointed out in the appended claims.

In the accompanying drawings Figure 1 is a bottom plan view of a ribbon-actuating mechanism constructed in accordance with the invention; the parts of said mechanism 45 being shown in midway or neutral position, and in which position of said parts, the ribbon is not wound upon either of the ribbon spools in the operation of the machine; Fig. 2 is a like plan view of the parts shown in Fig. 1; said parts being shown connected with one of the ribbon spool shafts, whereby the latter is turned to effect the movement of the ribbon in one direction upon the operation of the machine; Fig. 3 is a front ele-

vational view of the parts shown in Fig. 1; Fig. 4 is a sectional view taken on line 4—4 of Fig. 3; and Fig. 5 is a sectional view of a detail of construction.

Referring to the drawings, illustrating in detail, a ribbon-actuating mechanism constructed in accordance with the present invention, the same is shown in combination with and is adapted for rotating two vertical or upright ribbon-spool shafts 10, 10, arranged at each side of the machine, and through the medium of which the ribbon-spools (not shown) connected with said shafts are turned or rotated to effect the winding and unwinding of the ribbon first upon one and then upon the other of said spools in the operation of the typewriter. On the lower ends of said ribbon-spool shafts 10, 10 are affixed gear-pinions 11, 11. Said ribbon-spool shafts 10, 10 are rotated or turned through the medium of a horizontal, transversely arranged worm-shaft 12, upon the opposite ends of which are mounted and rigidly secured worm-gears 13, 13; one provided with right-hand worm-teeth and the other with left-hand worm-teeth. The worm-shaft 12 is adapted to be oscillated or swung horizontally about a vertical axis so as to effect the engagement of first one and then the other of said worm-gears 13, 13 with the gear-pinions 11, 11, or to simultaneously disconnect both of said worm-gears from said gear-pinions. For this purpose, said worm-shaft 12 is mounted in an oscillating bearing-member 14, preferably having the form of a horizontally arranged plate, and pivotally supported at its center so as to swing in a horizontal plane. Said bearing-member 14 is provided at its ends with depending arms or lugs 15, 15 in which said worm-shaft 12 is journaled. As illustrated, the worm-shaft 12 extends between and beyond said arms 15, 15 and is retained from endwise movement by means of a collar 16, rigidly secured to said shaft and confined between one of the arms 15 and a stop-flange 17 attached to said bearing-member 14. Said collar 16 is secured to said worm-shaft 12 by means of a set screw 16a. Said bearing-member 14 is pivotally connected with a fixed, horizontal bracket-member 18 by means of a vertically disposed pivot bolt 19. As shown in Fig. 4, said bracket-member 18 has adjustable ele-

nection with a transverse frame-member 20, on the machine base, by means of a bolt 21 inserted through said frame-member 20 and through an elongated slot 22 in said bracket-member 18.

5 When one worm-gear 13 is engaged with the associated gear-pinion 11, the other worm-gear is disengaged from its associated gear-pinion; the worm-shaft 12 being 10 rocked horizontally through the swinging of the bearing-member 14 to effect this result. (See Fig. 2.) When the worm-shaft 12 is arrested and held in an intermediate 15 position both the worm-gears 13, 13 are disengaged from the gear-pinnions 11, 11, and the ribbon-spool shafts 10, 10 are free to be rotated independently of the worm-shaft 12. (See Fig. 1.)

The worm-shaft 12 is rotated by means of 20 a pawl and ratchet mechanism operated from the universal bar of the machine, a portion of the universal bar being indicated by 23 in the drawings (Figs. 3 and 4). As shown, the ratchet mechanism comprises a 25 ratchet wheel 24 rigidly secured to the worm-shaft 12 between the depending arms 15, 15, and said ratchet wheel is rotated by the action of two oppositely acting pawls 25, 26 arranged on opposite sides of said 30 ratchet wheel and pivoted to a bracket-member 27 attached to said universal bar. The universal bar 23 has connection with the letter spacing mechanism and has rising and falling movement imparted to it upon 35 the operation of the key-levers and space-bar of the machine as is usual in typewriting machines. The pawls 25, 26 are held engaged with the ratchet wheel 24 by means of a spring 24^a connected with the pawls in 40 a manner to draw the free ends thereof together. (See Fig. 4).

For the purpose of effecting the rocking of the bearing-member 14, horizontally to alternately connect and disconnect the 45 worm-gears 13, 13 and the gear-pinnions 11, 11 means are provided as follows: horizontally disposed and arranged to extend transversely of or across the machine base and forward of the bearing-member 14, is 50 an endwise movable operating or shift-rod 28, the opposite ends of which extend through and slide in the side walls 29, 30 of the machine base; the ends of said rod 28 extending beyond said side walls, so that 55 they may be pressed upon by the hand of the operator for the purpose of pushing the rod endwise. In an "Oliver" typewriting machine, said walls 29, 30 constitute the side walls of the machine base and together with 60 the top, front and rear walls form a hollow machine base in which the parts herein described and shown are located. Adjustably connected with and extending from the central part of the bearing-member 14 toward 65 the rod 28 is a flat horizontal plate 31, pro-

vided with longitudinally spaced, outwardly projecting fingers 32, 33. The outer ends of said fingers bear against cam-members 34, 34, preferably in the form of conical collars, which are mounted on and rigidly secured by set screws 35, 35, to the rod 28. (See Figs. 1 and 2.) The said cam-members and fingers are located at opposite sides of the pivotal axis of the bearing-member 14 and equidistant therefrom. The said plate 31 is adjustably connected with the bearing-member 14 by means of fastening screws 36, 36 threaded into said bearing-member 14 from the under side thereof and through elongated slots 37, 37 in said plate 31. (Fig. 5.) By connecting said plate 31 with the bearing member 14 in the manner above described, the fingers 32, 33 may be adjusted toward and away from the cam-members 34, 34 for the purpose of taking 85 up wear on the ends of said fingers and for maintaining the ends of the same in proper engagement with said cam-members. The cam-members 34, 34 are alike and each have bearing surfaces for contact with its associated finger. Each cam-member has three parts at different distances from the longitudinal axis of the rod 28, to wit, a lower part 38, a higher part 39 and an intermediate part 40; the lower part 38 being nearest 90 the outer end of the rod, the higher part 39 being nearest the center of the length of the rod, and the intermediate part 40 being located between the parts 38 and 39. These parts are joined by inclined portions of the 95 bearing surface as is usual in the construction of cams. Each cam-member is preferably made in the form of a collar on said rod having a hub portion 41 at its inner end, through which the clamp screw 35 is 100 inserted, the lower part 38 having the form of a cone at the outer end of the collar, the intermediate part 40 being cylindric, and the higher part 39 having the form of an annular rib between the intermediate part 105 40 and the hub 41. Said higher part 39 is made inclined or conical on both of its sides, or in the form of a double cone, for a purpose hereinafter set forth. In the endwise movement of the rod 28 in one direction, 110 one of the fingers 32 or 33 bearing against the adjacent cam-member, in passing from the lower to the higher part of the cam-member, throws the adjacent end of the bearing-member 14 away from the rod, 115 thereby swinging said bearing member 14 on its vertical axis in one direction. The other finger operates in the same manner upon the other cam-member in the endwise movement of the rod 28 in the opposite 120 direction.

The plate 31 is provided with an integral stop-projection 42 located between and in the same plane with the fingers 32, 33; said projection 42 having at its end outwardly 130

and laterally facing stop-shoulders 43, 43 located in the paths of movement of the hubs 41, 41. Said stop-shoulders 43, 43 are adapted to contact with the inner end of 5 the hubs 41, 41 in the endwise movement of the actuating or shift rod 28 and act to limit the endwise movement of said rod in both directions, when the higher part or rib 39 of the one cam-member is in contact with 10 the end of its associated finger, (Fig. 2). The inner ends of the hubs 41, 41 form in effect stop-shoulders on the rod, while the stop-shoulders 43, 43 on the plate 31 are in effect stop-shoulders on the bearing-member 15 14.

When the several parts of the mechanism are in the position shown in Fig. 1, the ends of the fingers 32, 33 bear against the intermediate parts 40, 40 of both cam-members 20 34, 34 and the stop-shoulders 43, 43 of the bearing-member 14 are out of contact with said stop-shoulders. In this position of the parts, both gears 13, 13 on the actuating-shaft 12 are disconnected from the gears 11, 25 11 on the ribbon-spool shafts 10, 10, and said latter shafts may be rotated independently of the actuating-shaft 12. This position of the parts may be termed midway or neutral positions, as the ribbon is not wound 30 upon either of the spools in the operation of the typewriter. To swing the actuating-shaft 12 horizontally from its position shown in Fig. 1 to that shown in Fig. 2, so as to effect the engagement of the gear 13 35 at the right of said shaft 12 with the correspondingly located gear on the ribbon-spool shaft at the right of the machine the shift-rod 28 is moved endwise toward the left by pushing inwardly on the right-hand end of 40 the rod which extends beyond the side wall 30. In this movement of the rod 28, both cam-members 34, 34 are moved toward the wall 29 at the left side of the machine and finger 32 nearest said wall 29, passes from 45 the intermediate part 40 of the associated cam-member 34 over the higher part or rib 39 of same cam-member and is stopped when past the annular edge of said rib and bearing-against the inner inclined surface of the 50 rib by the stop-shoulder on the rod formed by the inner end of the hub 41 on the other cam-member coming into contact with the adjacent stop-shoulder 43 on the bearing-member 14. In the passing of said finger 32 over the said rib or higher part 39 of said associated cam-member the adjacent end of the bearing-member 14 is moved away from the rod and the bearing-member 14 swung in a direction to effect the engagement of 55 60 the said right-hand gear 13 with the said associated gear 11, (Fig. 2). The opposite end of the bearing-member 14 is at the same time moved toward the rod and the other finger 33 passes from the intermediate part 65 40 of the associated cam-member 34 to the

lower part 38 of the same cam-member in the endwise movement of the rod toward the left. The gear 13 at the left end of the actuating shaft 12 is at this time disconnected from the correspondingly located 70 gear 11.

With the shaft 12 operatively connected with the ribbon-spool shaft 10 located at the right of the machine, as above described, said ribbon-spool shaft will be turned or rotated upon the rotation of the shaft 12 and the ribbon wound upon the spool connected with said ribbon-spool shaft 10 and unwound from the spool connected with the oppositely located ribbon-spool shaft, which is disconnected from said shaft 12. A reversal of 75 the direction of movement of the rod 28 so as to cause the other finger to pass from the lower part over the higher part of the associated cam-member will effect the oscillation or swinging of the bearing-member 14 in the opposite direction and cause the engagement of the gear at the left end of the shaft 12 with the gear on the correspondingly located ribbon-spool shaft 10, and as 80 a result effect a reversal of movement of the ribbon.

In order to hold the cam-members 34, 34 at all times yieldingly in contact with the ends of the fingers 32, 33 so as to lock the rod 28 from accidental endwise movement and prevent shifting of the parts through the jarring of the typewriter while in use the rod 28 is made of spring metal and is capable of flexing laterally toward and from the fingers as said fingers pass over the higher parts or ribs 39 of said cam-members. When the end of one finger bears against the inner inclined surface of the associated rib and slightly beyond the annular edge of said rib, as shown in Fig. 2, that surface of the cam-member is held yieldingly in contact with the end of said finger by reason of the rod being resilient and the annular edge of the rib projecting inwardly beyond the 100 105 end of said finger forms in effect a shoulder against which the finger bears and the rod is locked from accidental endwise movement in a direction to effect the passing of the finger over the annular edge of said rib. 110 Likewise, the forward edge of the cylindric or intermediate part 40 of the other cam-member forms in effect a shoulder against which the end of the other finger bears when said finger is in contact with the inclined 115 surface of the lower part 38 of said other cam-member and the rod is further locked from being accidentally moved endwise in the direction referred to. The contacting of one stop-shoulder 43 on the bearing-member 14, with the associated stop-shoulder on the rod prevents endwise movement of the rod in the opposite direction. The rod being 120 125 resilient, the intermediate portions 40 of the cam-members 34, 34 when in engagement 130

with the ends of the fingers are held yieldingly in contact with said fingers, and the fingers engaging said intermediate portions at the base of the outer inclined surface of 5 the adjacent higher parts or ribs 39, the rod is locked from accidental endwise movement in a direction to cause one finger to pass over the higher part or rib 39 of the associated cam-member. It follows therefore, that the 10 resilience of the rod has the function of effecting the locking of the rod from endwise movement in either of the three positions into which the frame member may be swung, and the shifting of the parts from 15 any one of said three positions, through the jarring of the typewriter while in use, is prevented.

It is to be understood that the details of construction in the device herein illustrated 20 and described may be variously modified without departing from the spirit and scope of our invention, and that the invention is not to be limited to the details of construction and arrangement shown, except as 25 pointed out in the appended claims.

We claim as our invention:

1. In a typewriting machine, a ribbon-spool actuating mechanism embracing two gear-pinions, a rotative actuating shaft mounted for oscillatory motion about an axis transverse to its axis of rotation, and provided with gears adapted for alternate engagement with and disengagement from 30 said gear-pinions, an endwise movable operating rod mounted to slide endwise in the machine frame, and means for transmitting motion from said rod to the actuating shaft, to give swinging movement to the latter in the endwise movement of the rod, comprising 35 two cam-members, and two movable fingers in contact with the same, said cam-members and associated fingers being located at opposite sides of the axis of oscillation of the actuating shaft.

2. In a typewriting machine, a ribbon-spool actuating mechanism embracing two gear-pinions, a rotative actuating shaft mounted for oscillatory motion about an axis transverse to its axis of rotation, and 50 provided with gears adapted for alternate engagement with and disengagement from said gear-pinions, an endwise movable operating rod mounted to slide endwise in the machine frame and projecting at its ends 55 beyond the opposite outer surfaces of said frame, and means for transmitting motion from said rod to the actuating shaft, to give swinging movement to the latter in the endwise movement of the rod, comprising two 60 cam-members carried by said rod, and two movable fingers in contact with the same, said cam-members and associated fingers being located at opposite sides of the axis of oscillation of the actuating shaft.

3. In a typewriting machine, actuating

mechanism for the ribbon-spool shafts, comprising two gear-pinions through which said spool-shafts are given rotary movement, a rotative actuating shaft, a bearing member for said shaft, mounted to oscillate on an 70 axis transverse to the axis of rotation of said actuating shaft, said shaft being provided with gears adapted to be moved into and out of engagement with the said gear-pinions by the oscillatory movement of the 75 shaft, an endwise movable rod provided with two cams located at opposite sides of the axis of oscillation of the bearing-member and fingers on the bearing member acting on said cam-members, whereby the endwise movement of said rod will effect oscillatory movement of said bearing member and actuating shaft.

4. In a typewriting machine, actuating mechanism for the ribbon-spool shafts, comprising two gear pinions through which said spool-shafts are given rotary movement, a rotative actuating shaft, a bearing member for said shaft, mounted to oscillate on an axis transverse to the axis of rotation 90 of said actuating shaft, said shaft being provided with gears adapted to be moved into and out of engagement with the said gear-pinions by the oscillatory movement of the 95 shaft, an endwise movable actuating rod 100 mounted to slide endwise in the machine frame and projecting at its ends beyond the opposite outer faces of said frame, and means for transmitting motion from said rod to the bearing-member to give oscillatory movement to the latter in the endwise movement of the rod, comprising a cam-member on the rod and a finger on the bearing member adapted for contact with said 105 cam-member.

5. In a typewriting machine, actuating mechanism for the ribbon-spool shafts, comprising two gear-pinions through which said spool-shafts are given rotary movement, a rotative actuating shaft mounted for oscillatory movement about an axis transverse to its axis of oscillation and provided with gears adapted to be moved into and out of engagement with said gear-pinions by the oscillatory movement of the shaft, an endwise movable rod provided with two cams located at opposite sides of the axis of oscillation of the bearing-member, fingers on the bearing-member acting on said cam-members, said rod being resilient and adapted 115 for lateral flexure, to maintain said cams in contact with said fingers.

6. In a typewriting machine, actuating mechanism for the ribbon-spool shafts, comprising gear-pinions, an actuating shaft provided with gears adapted to be moved into and out of engagement with said gear-pinions, a bearing-member for said shaft, having oscillatory movement about an axis transverse to the axis of rotation of the 120

125

130

- shaft, and means for oscillating said bearing member embracing an endwise movable rod provided with two cam-members and fingers on the bearing-member, in contact with and adapted to be acted on by said cam-members in the endwise movement of said rod, said rod being provided with stop-shoulders and the bearing-member provided with a stop-plate having stop-shoulders for contact with the stop-shoulders on the rod.
7. In a typewriting machine, actuating mechanism for the ribbon-spool shafts comprising gear-pinions, an actuating shaft provided with gears adapted to be moved into and out of engagement with said gear-pinions, a bearing-member for said shaft, having oscillatory movement about an axis transverse to the axis of rotation of the shaft, and means for oscillating said bearing-member embracing an endwise movable actuating rod provided with two cam-members

bers and fingers on the bearing-member, in contact with and adapted to be acted on by said cam-members in the endwise movement of said rod, each of said cam-members having a cam projection over which its co-acting finger passes in the endwise movement of the rod, and the rod being resilient to permit lateral flexure thereof and effect the locking of the rod from endwise movement through the engagement of said finger with said cam projection.

In testimony, that we claim the foregoing as our invention we affix our signatures in the presence of two witnesses, this 17th day of January A. D. 1914.
